United States Patent Office

Des. 205,279

Patented July 19, 1966

205,279

ILLUMINABLE SIGN

Robert T. P. Kane, Casper, Wyo., assignor to Convenient Food Mart, Inc., Chicago, Ill., a corporation of Illinois

Filed Sept. 16, 1965, Ser. No. 87,030

Term of patent 14 years

(Cl. D1—12)

I claim:

The ornamental design for an illuminable sign, as shown.
